UNITED STATES PATENT OFFICE.

CHARLES G. ANDERSON, OF OGDEN, UTAH.

DESIGN FOR A MEMBER FOR CUTTING AND ADJUSTING TOOLS.

SPECIFICATION forming part of Design No. 31,788, dated November 7, 1899.

Application filed January 18, 1899. Serial No. 702,593. Term of patent 14 years.

To all whom it may concern:

Be it known that I, CHARLES G. ANDERSON, a citizen of the United States, residing at Ogden, Utah, have invented and produced a new 5 and original Design, Shape, or Conformation for a Member for Cutting and Adjusting Tools, of which the following is a specification, reference being had to the accompanying drawings, which form a part of this application, o and in which—

Figure 1 is a plan view of one side of a tool member made in accordance with my design, and Fig. 2 is a plan view of the reverse or opposite side of said member.

5 As shown in the drawings, the leading features of my new tool member consist of the jaw portion *a*, the handle portion *b* forming a continuation of the jaw portion and various indentures, openings, and grooves cut in the o said jaw and handle portions, respectively, as will be pointed out. The jaw portion *a* has flat and parallel sides, except for the beveled portion *a*² on one side of the end portion of the jaw and the V-shaped recess in the 5 same side of the jaw. In the lower edge of

the jaw are three nicks or openings *a*⁴, *a*⁵, and *a*⁷, the central nick *a*⁵ of which has a notch *a*⁶ cut in the bottom of the nick, and the nick *a*⁷ is formed with flaring sides. Near the junction of the handle and the jaw is a rivet-hole *b*', and on the upper edge is a slot *b*², having parallel and beveled sides. The end of the handle has a longitudinal groove formed therein. The opposite side of the tool member is exactly like the side above described, 35 except that it has no beveled portion *a*² and no recess *a*³, and at the apex of the nick *a*⁷ a crescent-shaped groove *a*⁸ is formed.

Having described my invention, what I claim as new, and desire to secure by Letters 40 Patent, is—

The design for a member of a cutting and adjusting tool substantially as described and shown.

In testimony whereof I affix my signature 45 in presence of two witnesses.

CHARLES G. ANDERSON.
